UNITED STATES PATENT OFFICE.

CLARENCE D. PLATT, OF BRIDGEPORT, CONNECTICUT.

INCLOSED SWITCH CONSTRUCTION.

1,170,990.

Specification of Letters Patent.

Patented Feb. 8, 1916.

Application filed July 15, 1915. Serial No. 39,966.

To all whom it may concern:

Be it known that I, CLARENCE D. PLATT, a citizen of the United States of America, residing at Bridgeport, Connecticut, have 5 invented a new and useful Inclosed Switch Construction, of which the following is a specification.

The main object of my invention is to provide a box or enclosure for a switch construction, the parts being arranged and constructed so that the switch may be operated when the box is closed and so that the switch may be locked in the open position when the box is closed.

15 Another object is to prevent the opening of the box when the switch is in its closed position.

Another object is to provide a simple and reliable construction which may be conveniently operated.

In the preferred form as herein shown, the switch proper has a pivoted blade member and is mounted within a box having a hinged cover. An outer U-shaped handle is 25 pivoted in the sides of the box and connected by a U-shaped frame on the interior to the switch blade through the medium of an insulating member. The ends of the U-shaped members are secured to disks located 30 in bearings in the sides of the box in alignment with the pivot of the switch blade. The cover of the box may be locked closed with the switch open so as to prevent the switch from being closed. When the outer 35 handle is not locked the switch may be operated with the box closed but the outer handle in closing the switch is brought across the cover so that the cover cannot be opened until the switch is opened.

40 Figure 1, is a front view of the construction embodying the improvements of my invention, the cover being shown closed and the switch handle locked in the "open" circuit position. This figure also shows in 45 dotted lines the position of the outer handle when the switch is in its closed circuit position. Fig. 2, is a front view of the construction with the cover open and the switch in its open circuit position. Fig. 3, is an en-

50 larged sectional view showing the method of supporting the outer handle in the side wall of the box. Fig. 4, is a vertical sectional view of the construction showing the switch in its closed circuit position. This view also shows in dotted lines the cover

open and the switch in its open circuit position. Fig. 5, is a perspective view of the operating handle and the connections to the switch blade.

The switch construction proper may be of 60 any satisfactory type. In this case it consists of the pivoted blades 10 and the stationary contacts 11. These together with the usual safety devices or fuse plugs 12 are mounted on an insulating base 13 and provided with suitable terminals for connection to the main and branch circuits as usual.

The parts are mounted in the box 14 and secured for instance by means of a number of screws such as 15. The cover 16 is hinged 70 at 17 and provided with a perforated lug 18 adapted when the cover is closed to lie alongside of the perforated lug 19 on the body of the box so as to receive the hasp of a suitable lock 20.

75 The switch is operated by means of a frame consisting of the inner U-shaped member 21 and the outer U-shaped member 22. The ends of these U-shaped members are secured to disks 23 for instance by 80 means of rivets such as 24 and the disks are mounted in circular openings in the side walls of the box in line with the pivotal supports of the blades 10. The inner member 21 is connected by the member 25 to the 85 insulating bar 26 which connects the ends of the blades 10. The twisted cross bar part 27 of the outer U-shaped member 22 forms a convenient handle for operation of the switch from the exterior of the box.

90 It will be noted from the foregoing that when the box is closed and the switch is in its closed circuit position, the cover cannot be opened because of the cross bar 27 which acts as a guard. This prevents the opening 95 of the box and tampering with the switch and the possibility of accident when current is flowing through the parts.

When it is desired to prevent tampering with the switch or removal of safety devices, 100 the cover may be locked closed.

When it is desired to prevent any one from closing the switch and using current, the switch is opened and locked open by passing the hasp of the lock through a perforation 28 in the switch handle or by simply engaging the switch handle beneath the lock, as shown in Fig. 1.

105 The method of supporting the handle in the sides of the box is inexpensive and makes 110

a rigid, durable construction not likely to be bent or thrown out of commission, even by rough handling.

By extending the edges of the members 21 and 22 beyond the rims of the bearing disks 23, as indicated in Figs. 2 and 3, said disks are held against being displaced inwardly or outwardly in the bearing openings in which they are seated.

10. What I claim is:—

1. In combination, a switch having a pivoted switch blade, a casing inclosing said switch and having openings in the opposite walls thereof in line with the pivot of the pivoted switch blade, relatively flat disks rotatably engaged in said openings, a U-shaped member inside the casing having side arms connected by a cross bar, the ends of said side arms being secured in engagement with the inner relatively flat sides of the rotatable disks and thereby preventing outward displacement of said disks in the openings in which they are seated, a connection between the cross bar and the pivoted switch blade, an operating U-shaped member outside the casing having sides connected by a cross bar, the ends of said sides being secured to the outer relatively flat surfaces of the rotatable disks, and thereby preventing inward displacement of said disks in the openings in which they are seated, and said cross bar extending across the front face of the switch casing and serving as a handle for operating the switch.
2. The combination of a switch, an inclosure therefor having a pivoted cover, an external operating handle for said switch, said inclosure and cover having holes adapted to be brought into alinement by the closing of the switch inclosure, a locking device insertible into said alined holes to lock the switch inclosure closed, and the said switch operating handle adapted to be thrown into

a position beneath the alined holes, whereby upon the engagement of the locking device 45 in said holes, said switch operating handle will be locked in position beneath said locking device.

3. The combination of a switch, an inclosure for said switch having a hinged 50 cover, an external handle for operating said switch, said inclosure and cover having lugs adapted to be brought into alinement by the closing of the switch inclosure, and a locking device engageable with said alined lugs, 55 and with the operating handle to lock the inclosure closed and the switch in the position to which it has been thrown by the operating handle.

4. The combination of a switch, a casing 60 inclosing said switch having a bearing opening in one wall thereof, a relatively flat disk rotatably engaged in said bearing opening, a switch operating member inside the casing secured in flat engagement with the inner relatively flat face of the disk and extending beyond the rim of said disk to thereby prevent outward displacement of said disk in the opening in which it is seated, and a switch operating handle outside 70 the casing secured in flat engagement with the relatively flat outer face of the disk and extending beyond the rim of said disk to thereby prevent inward displacement of said disk in the opening in which it is seated. 75

5. The combination of a switch, an inclosure therefor having a pivoted cover, an external operating handle for said switch, said box, said cover and said handle having holes adapted to be brought into alinement 80 for locking the box closed and the switch in open circuit position.

CLARENCE D. PLATT.
